VARIABLE SPEED TORPEDO

John Hays Hammond, Jr., Gloucester, Mass.

Application April 6, 1929, Serial No. 353,005

Renewed April 9, 1932

28 Claims. (Cl. 114—21)

This invention relates to the control of self-propelled moving bodies, and more particularly to a new and improved means for controlling the action of a torpedo.

5 The invention provides a control device which becomes effective when the torpedo misses its objective and operates to redirect the torpedo for producing a hit. For this purpose the antenna which is commonly employed for controlling a 10 torpedo by wireless is used as a redirecting means and is adapted when under the influence of an external mass of magnetic material, such as a ship's hull, to modify the movement of the torpedo.

15 In the case of a direct strike, the redirecting antenna is obviously unnecessary. In case the torpedo misses the target, the trailing antenna will come under the influence of the ship's hull and cause the torpedo to turn about and strike 20 the ship from the opposite side. The angle through which the torpedo must be turned may be predetermined from a knowledge of the speed of the ship and the speed of the torpedo, and means is provided for manually setting the apparatus to this angle before the torpedo is fired. 25 The apparatus is also set to turn the torpedo either to the right or to the left according to the direction of movement of the target.

The invention further provides means controlled from a distance to render the trailing antenna effective for the above mentioned purpose, after the torpedo nears its objective. The antenna may consequently be used for wireless control until the torpedo approaches the enemy 30 ships, and may then be transferred to the redirecting mechanism, thereby rendering a hit practically certain.

A variable speed mechanism is also provided for changing the speed of the torpedo for a predetermined period whereby it may be advanced 40 or retarded with respect to the other torpedoes of the salvo. The variable speed mechanism may be operated by remote control from the trailing antenna.

45 The invention also consists in certain new and original features of construction and combinations of parts, hereinafter set forth and claimed.

Although the novel features which are believed 50 to be characteristic of this invention will be particularly pointed out in the claims appended hereto, the invention itself, as to its objects and advantages, the mode of its operation and the manner of its organization, may be better understood 55 by referring to the following description taken in

connection with the accompanying drawings forming a part thereof, in which

Fig. 1 is a diagrammatic sectional view of a portion of a torpedo embodying features of the present invention;

Fig. 19 diagrammatically illustrates the course of the torpedo after engagement of the antenna with the target;

Fig. 20 shows a battle line of ships being attacked by self-propelled bodies embodying features of the present invention; and 40

Fig. 21 is similar to Fig. 20 with a different formation of the attacking torpedoes.

Like reference characters denote like parts in the several figures of the drawings.

In the following description and in the claims parts will be identified by specific names for convenience, but they are intended to be as generic in their application to similar parts as the art will permit.

Referring to Fig. 1, there is shown a water borne body forming a carrier of explosives, having a water-tight torpedo hull 10, and arranged to be propelled by a pair of propellers 11, 11. The propellers 11 are mounted on a pair of con-

centric shafts, including an outer shaft 12, and an inner shaft 14. The shafts 12 and 14 are directly connected to a driving means 15. The driving means 15 preferably takes the form of a conventional compressed air turbine, the actuating fluid being delivered thereto through reducing valve V, retarding mechanism R and pipe 16. A gear 17 is keyed to the outer shaft 12 for operative engagement with gears 18 and 19 to cause rotation of shafts 20 and 22, as will hereinafter be described.

Horizontal rudders for varying the direction of movement of the torpedo about its horizontal transverse axis may also be provided in a well-known manner, but as such rudders and depth control devices for controlling the same are well known, it is thought that a more detailed description thereof is unnecessary herein.

For varying the direction of movement of the torpedo about a vertical axis so as to steer the torpedo in azimuth, there is provided a pair of blade rudders 30 pivotally mounted upon a pair of rotatable vertical rudder posts 31, whereby the rudders 30 can be moved relative to the torpedo to control the direction of movement thereof. The rudder posts 31 are shown rigidly connected by a yoke 32 (see Fig. 4) which may be shifted according to requirements by a connecting rod 33 having one end pivotally connected thereto. The other end of the connecting rod 33 is pivotally secured to a piston rod 34 of a piston 35 which is mounted for reciprocating movement in a cylinder 36. Adjacent the ends of the cylinder 36 are provided ports 37, 38, which are controlled by a slide valve 39 operating in a fluid pressure chest 40, which is in communication with a source of fluid pressure 41. The arrangement is such that the piston 35 is moved to the right or to the left according to the position of the valve 39 with respect to the ports 37, 38. The respective ports of the cylinder 36 exhaust by way of the open ends of the valve chest 40, when the valve 39 has been moved to full open position in either direction.

For actuating the slide valve 39 and also for maintaining it in position to cause the torpedo to move upon a predetermined course, two mechanisms are employed, one operating automatically under control of a stabilizing device and the other operating at the will of an operator under distant control. The parts common to the two mechanisms include an extension 50 of the slide valve 39, and having its outer end operatively connected to the free end of a rocking arm 51, the other end of which is securely fastened to a rock shaft 52 pivotally mounted in a fixed bracket 53.

As more clearly illustrated in Figs. 9 and 10, for actuating the rock shaft 51 there is provided a lever arm 60 terminating in a ball 61, which is straddled by the bifurcated end of a bell crank 62, movement of which causes the shaft 52 to rock in a desired direction. The bell crank 62 is pivotally mounted on a bracket 63 which is secured to the outer face of a rotatable cover plate 64. The cover plate 64 is mounted on a housing 65 by means of a pin 66 which is screwed into a bracket 67 of the housing 65. Pivoted to the lower arm of the bell crank 62 is a link 68, the opposite end of which is pivotally connected to an L shaped member 70 rotatably mounted upon a vertical pin 71 of the cover plate 64. A similar member 72 is pivoted to the cover plate 73. For actuating member 72 a link 74 is pro-

vided pivotally connected to the inner ends of the members 70 and 72. Slidably mounted between the feet of the bracket 63 is a reciprocating plate 75 in which is rotatably mounted a member 76, the upper end of which is provided with a finger 77 which, when the plate 75 is reciprocated, engages either the member 70 or the member 72. The lower end of the member 76 is provided with two fingers 78 and 79, which are located in two planes, one above the other. The plate 75 is provided with a slot 80, which surrounds a cam 81, rotatably mounted on the pin 66. The upper part of the cam 81 is provided with a beveled gear 82 adapted to mesh with a second beveled gear 83 secured to the end of the shaft 22 having a bearing in the bracket 53. The shaft 22 is provided with a gear 19, which meshes with the gear 17 secured to the shaft 12.

Within the housing 65 is pivotally mounted a vertical gimbal ring 90, within which a horizontal gimbal ring 91 is mounted bearing rotating massive element 95. Secured to the vertical gimbal ring 90 is a circular plate 96 cut away on either side as at 97 and 98. The cut away portions are arranged in different horizontal planes such that the cut away portion 97 lies in the same plane as the finger 78 and the cut away portion 98 lies in the plane of the finger 79. When the torpedo is discharged, the element 95 is set in rotation by means of a driving mechanism not shown, which is automatically disconnected as the element is brought up to the desired speed. The gyroscopic action of the element 95 will tend to keep its axis in a fixed direction in space. Thus the plate 96 will always remain in its original position regardless of a change in direction of the torpedo.

For controlling the valve 39 by the above described apparatus the shaft 22 is rotated at a high speed by means of the gears 17 and 19, causing the beveled gear 83 and cam 81 to rotate rapidly. Rotation of the cam 81 imparts a corresponding rapid reciprocation to the plate 75, carrying with it the member 76. Thus, as the torpedo continues on a straight course, the fingers 78 and 79 will move in and out of the cut out portions 97 and 98 of the plate 96, without affecting the position of the member 76 or the finger 77, which will reciprocate between the ends of the members 70 and 72 without changing their positions. If the torpedo should deviate from a straight course, say for example to the left, the casing 65 being carried by the torpedo will be rotated in a counter-clockwise direction, thus carrying with it the member 76. As the fingers 78 and 79 are moved back and forth the finger 78 will strike the plate 96 at a part where it is not cut away, thus causing a relative rotation of the member 76, in a counter-clockwise direction, which in turn will rotate the finger 77 in a like direction. As this reciprocates it will strike the end of the member 72 rotating it in a counter-clockwise direction, which by means of the link 74 will rotate the member 70 in a like direction, thus causing the link 68 to be moved to the right, causing the bell crank 62 to be rotated in a counter-clockwise direction, thereby rotating the shaft 52 in a clockwise direction by the connection therewith of the ball 61 and arm 60.

By referring to Figs. 1 and 2 it may be readily seen that by connection of the arm 51 to the shaft 70 rotation of the shaft 52 causes movement of the arm 51, thus moving the valve 39 to the left. This will uncover the ports 37 and 38, thus allowing air to enter the left-hand side of the cylinder 36 and pass from the right hand side, causing

the piston 35 to be moved to the right which, by means of the piston rod 34 and the rod 33 will cause the rudders 30 to be moved to the right, thereby restoring the torpedo to its course.

5 If the torpedo deviates to the right a similar action, but in the opposite direction, will take place, causing the rudders to be moved to the left. In this way, the torpedo is maintained upon a pre-determined straight course under the control 10 of the gyroscopic element 95.

For actuating the slide valve 39 at will, for example from a station distant from the torpedo, the cover 64 has a portion of its periphery toothed as at 100, which is in mesh with a worm 101 integral with a shaft 102 (see Fig. 14). The shaft 102 is journaled in spaced bearings 104, 104 and terminates in a beveled gear 105, which is in mesh with a gear 106 mounted on a rotatable shaft 107, which is journaled in a bearing 108.

20 The shaft 107 is also journaled in a bracket 110 (Fig. 2) secured to the hull of the torpedo, the shaft 107 being provided with spaced ball thrust bearings 111-112. The shaft 107 terminates in a releasable clutch mechanism, whereby 25 when in the position shown in Fig. 2, rotation of the shaft 107 is dependent upon rotation of a shaft 120 upon which one portion of the clutch mechanism is mounted.

The opposite end of the shaft 120 protrudes 30 into a compartment 121 shown in Fig. 1 and has fixedly secured thereto a pair of ratchets 122, 124, see Figs. 2 and 3, arranged in reversed relation so that one may turn the shaft 120 in a clockwise direction and the other can turn the 35 shaft in a counter-clockwise direction. The operating means for these ratchets consists of a gear 125 loosely mounted upon the shaft 120 between the ratchets, and having on opposite faces pivoted pawls 126-128 for engaging the ratchets 40 122-124 respectively. Each of the pawls is yieldingly maintained in engagement with its respective ratchet by a spring such as 129. In order to cause either pawl to be moved from engagement with its ratchet so that the shaft 120 can be 45 turned in one desired direction without interference from the other pawl and ratchet, the pawls are respectively provided with laterally disposed lugs 130, 131, with which are respectively arranged to engage trip members 132-133, which 50 are secured to the wall of the compartment 121. From the foregoing it will be apparent that if the gear 125 is moved in a clockwise direction through an angular distance of 180° that the pawl 126 will engage its ratchet 122 and likewise turn the 55 shaft 120 through an angular distance of 180°. Similarly if the gear 125 is moved in a counter-clockwise direction through 180° the pawl 128 engages its ratchet 124, and turns the shaft 120 one-half a revolution in a counter-clockwise direction. While turning in a clockwise direction, the lug 131 of the pawl 128 engages one face of the respective trip member 133, and thus during the turning movement of the gear 125, the pawl 128 is oscillated about its pivot in a clockwise 65 direction, and thus will be held out of engagement with the ratchet 124, so that upon the return of the gear 125 to its normal position the pawl 128 will be held in inactive position with the respective ratchet and will not be engaged thereby. 70 Thus it will be seen that rotation of the gear 125 through an angular distance of 180° operates the shaft 120 in a similar manner, but that restoration of the gear does not restore the shaft.

For controlling movement of the loose gear 75 125 there is provided a reciprocating rack gear

140, having a lug 141 in engagement with a pair of restoring springs 142-143. The springs 142, 143 are mounted on a rod 144 and are held by brackets 146, 147 respectively secured to the compartment 121. Springs 142, 143 have substantially 5 equal tension, and serve to restore the rack 140 to normal position shown in Figs. 2 and 3. One end of the rack 140 is secured to a piston 150 snugly fitted for reciprocating movement within a cylinder 151. The ends of the cylinder are respectively provided with ports 152, 153, the port 152 being controlled by an electrically operated slide valve 154, and the port 153 being controlled by a similar valve 155. The slide valves 154, 155 are arranged to be actuated by solenoids 156-157 15 respectively, and each is provided with a retractile spring, such as 158. Each slide valve is arranged so that upon energization of the respective magnet, the valve port is connected to a branch pipe 160 leading to the supply source 20 116, and the piston 150 is moved accordingly. Upon release of the magnet the valve is restored by the action of the respective spring 158, and the valve port is connected to atmosphere through a vent 161. The piston is restored to its initial 25 position under control of spring 142, 143. The arrangement is such that actuation of piston 150 as just described moves the rack 140 sufficiently to rotate the gear 125 through an angular distance of slightly more than 180°, and thus 30 moves the shaft 120 one-half a revolution. The consequent turning of the cover plate 64, and movement of the arm 54 and rod 50 operates the rudder arm 33 to turn the torpedo 5°.

Referring to Fig. 13, for controlling the magnets 156, 157 selectively so as to steer the torpedo in either direction about its vertical axis at the will of a distant operator, the magnets are connected in circuit with a controller 170 and a source of energy such as a battery 171. The controller 170 comprises a commutator 172 having a cylindrical insulating base 173 mounted on a shaft 174. The shaft 174 is journaled in a pair of spaced brackets 175. A ratchet wheel 176 is rigidly secured thereto, and is engaged by a spring 45 177 pivotally mounted on a reciprocating stem 178. The stem 178 is slidably mounted near one end in a fixed bracket 179. At its other end the stem 178 is secured to a magnetic core 180 forming the armature of a solenoid 181. A collar 182 is pinned to the stem 178 and serves as an abutment for a compression spring 183 to restore the stem 178 and the armature 180 to normal. The collar 182 carries an insulating stud 184 which normally engages a contact spring 185 mounted on an insulating bracket. When engaged by the stud 184 in the normal position of the collar 182 the spring 185 is held against a second contact spring 186. When the collar 182 moves off normal, however, the stud releases the spring 185 which then disengages the spring 186 and opens the circuit. The arrangement is such that, upon energization of the solenoid magnet 181, the core 180 is moved to the right of Fig. 13, the pawl 177 being drawn inactively over the next tooth of the ratchet 176. Upon de-energization of the solenoid, the armature moves to the left under control of the spring 183 and the pawl 177 moves the ratchet 176 in a counter-clockwise direction as seen in Fig. 14. 65

A conducting plate 187 having segments 188 contacting in alternate positions of the ratchet 176 with a contact spring 189, and similar segments 190 contacting in the remaining positions with a contact spring 191, is mounted on the in- 70 75

sulating base 193, and is connected to a contact spring 192. The springs 189, 191, 192 are mounted on the insulating block 193.

Conducting plate 520 having segments 521 contacting in alternate positions of the ratchet 176 with a contact spring 522 and similar segments 523 contacting in the remaining positions with a contact spring 524, is also mounted on the insulating base 193 and is connected to a contact spring 525. Springs 522, 524 and 525 are also mounted on insulating block 193.

The inner end of the solenoid core 180 has secured thereto an extension 194, formed of non-magnetic material, and having an end protruding outwardly of the solenoid to engage one end of a dash pot rod 195. The rod 195 is slidably mounted in an end of a cylinder 196, and terminates therein in a piston 197, which is snugly fitted within the cylinder. One end of the cylinder has an open vent 198. The other end has a trap valve 199 arranged to permit the emission of air therefrom freely, but to prevent the entry of air. An adjustable passage 200 having a needle valve 201 permits the entry of air through the passage 200 at a regulated rate. A spring 202 mounted on the rod 195 tends to maintain the rod in its left-hand position. It will thus be seen that the piston 197 moves freely to the right, but that its return is delayed by the restricted flow of air through the needle valve 201. The outer end of the rod 195 carries a brush holder 203, one end of which is formed into a latch member 204. A contact brush 205 is carried by the holder 203, and makes sliding contact with a commutator 206. The commutator includes an insulating segment 207, upon which the contact brush 205 normally rests when the rod 195 is in its normal or initial position; a conducting segment 208, to which the brush 205 makes electrical contact when the rod 195 moves off normal a limited extent; and an insulating segment 209 over which the brush 205 sweeps when the rod 195 is moved to the right to a greater extent.

A second similar solenoid 210 is connected in multiple with the winding of the solenoid 181, and is mounted in spaced parallel relation thereto. The second solenoid 210 includes an armature core 211 formed of paramagnetic material, the general assembly being substantially similar to the assembly in combination with the solenoid 181. However, no trap valve is provided in the dash pot arrangement, so that movement of the core 211 is retarded in either direction. Mounted upon a collar such as 203 is a contact brush 212, which makes sliding contact with a portion of the commutator 206. The arrangement is such that in its normal position the brush 212 engages the conducting segment 208, and continues to engage this segment for most of its travel. Further movement of the rod carries the brush 212 into engagement with the insulating segment 209, after which, in the fully operated position of the rod the brush 212 engages a conducting segment 213.

For latching the second dash pot rod under control of the rod 195, the latch member 204 engages a spring-pressed latch 214, slidably mounted in bracket 215, and having secured thereto one end of a lever system 216, the arrangement being such that after the solenoids 181, 210 are energized for a sufficient length of time to permit the dash pot rods to be moved to the right to the full extent of their travel, the brush 212 will be held locked against retraction by the engagement

therewith of the lever system. In this position the brush 212 is on the insulating segment 213. The rod is maintained in this position until the other dash pot rod 195 returns to its initial position whereupon the latch member 204 pushes the latch member 214 outwardly against the tension of the spring. The consequent movement of the latch member 214 is communicated by the lever system 216, thus releasing the second dash pot rod, and permitting it to return to normal under control of its spring. Thus it will be seen that after the dash pot rods have been fully operated the brush 212 is maintained on the insulating segment 209, while the brush 205 is passing over the conducting segment 208. Thus no impulse is transmitted over the conductor 217.

For receiving radiant energy to operate the solenoids 181, 210 from a distant point, there is provided an insulated antenna 218 arranged to trail after the torpedo, during its movement through the water, the outer end being insulated to prevent grounding. The torpedo end of the antenna is connected to a flexible conductor 218A which normally engages a contact 218B which is connected to a tapped inductance 500, one terminal of which is grounded to the hull 10 of the torpedo. The other terminal of the inductance is connected through a variable condenser 501 to ground, thus forming an open oscillatory circuit, which may be readily tuned by adjustment of the condenser to the frequency of energy, which is to be received. The inductance is inductively coupled to a secondary winding 502, which is shunted by a variable condenser 503, and forms in combination therewith a secondary, closed oscillatory circuit, which may be similarly tuned to the frequency of the received energy by adjustment of the condenser. The secondary circuit is connected through a blocking condenser 504 to a three electrode thermionic device 505, preferably in the form of a so-called vacuum tube having an evacuated container, a cathode, shown in the form of a heated filament, for emitting electrons, a grid for controlling the passage of electrons and a plate upon which the electrons impinge. The plate or output circuit includes an amplifier 506 for amplifying the energy impressed thereon by the vacuum tube. The vacuum tube thus serves as a detector of received energy which may take the form of complex radiant energy of high frequency, having impressed thereon intermediate amplitude variations modulated in accordance with a signal. The modulated intermediate frequency thus appears in the output circuit of the rectifying tube and is amplified by the amplifier. The intermediate frequency is impressed upon an inductance 507, having in shunt therewith a variable condenser 508, the inductance and condenser forming in combination a closed oscillatory circuit which may be tuned to the intermediate frequency by adjustment of the variable condensers. The inductance is coupled to a tickler coil 509, which is included in the plate circuit of a vacuum tube oscillator 510, the input of which is connected to the inductance. The vacuum tube thus serves as a generator of the intermediate frequency which is combined with the modulated intermediate frequency in a second detector 511 to produce a low frequency current corresponding to the original modulating current. The output circuit of detector 511 includes an amplifier 512, the output of which is connected to the winding of a sensitive relay 219, the contact of which controls a local circuit including a source of energy 220, and the winding 75

of a secondary relay 221. The contacts of the secondary relay 221 are included in a circuit having connected in series therewith a source of energy, such as a battery 222, and the windings of the solenoids 181, 210 in multiple. It will thus be seen that when energy of pre-determined characteristic is impressed upon the antenna 218, it is amplified and detected and serves to operate the relay 219; and that the consequent operation of the relay 219 causes the operation of the secondary relay 221, which in turn causes the energization of the solenoids 181, 210 in multiple.

The circuit of the controller 170 includes a conductor 217 extending from the brush 192 to the contact spring 186. When the brush 205 engages the conducting segment 208 the circuit is extended to the brush 212, and a flexible conductor 231 to one pole of the battery 171, the other pole of which is connected by a conductor 232 to one terminal of each of the windings 156, 157 (see Fig. 3). The other terminal of the winding 156 is connected by a conductor 233 to the brush 191 of the controller 170. Similarly the other terminal of the winding of the other solenoid 157 is connected by conductor 234 to the brush 189 of the controller 170. A flexible conductor interconnects the contact spring 185 and the brush 205.

The segment 213, which is engaged by the brush 212 when the rod is moved to its full extent of travel, is connected by a conductor 240 to contact spring 525. Spring 524 is connected by conductor 526 to one terminal of a winding of a solenoid 241 (see Fig. 13), the other terminal of which is connected by conductor 242 to one pole of the battery 171. The solenoid 241 is provided with a spring controlled armature 241A which normally engages the flexible conductor 218A holding it in the position shown in Fig. 13. Spring 522 is connected by conductor 527 to solenoid 528 forming a part of the retarding mechanism R, thence by conductor 529 to battery 171. The retarding mechanism comprises a valve 530 through which the actuating fluid passes to the driving turbine. Valve 530 is controlled by rods 531 and 532, the former being held against cam 533 by spring 534. Cam 533 is rotated by clock-work mechanism, the speed of which is controlled by pointer 535. Solenoid 528, when operated, releases latch 536 which is then pressed inwardly by spring 531 and releases the clockwork, allowing cam 533 to rotate. The extent of movement of valve 530 is determined by cam 538 which cooperates with rod 532. At the end of a complete revolution cam 533 again forces rod 531 and valve 530 to the position shown in Fig. 13. Cam 538 is mounted on rod 539 (Fig. 2) which extends through the side of the hull 10 and may be manually set to the desired position.

Mounted upon the bracket 110, a shaft 300 is provided which projects through a portion of the bracket 110 and has securely mounted thereon a bevel gear 301. The shaft 300 is mounted for rotation in bearings in the bracket 110 and has secured thereto a dog 302 which rotates with the shaft 300. A spring 303 (see Fig. 2) is mounted on the shaft 300 and has its inner end secured to the shaft. Adjacent thereto is a ratchet wheel 304, which is loosely mounted on the shaft 300, the outer end of the clock spring 303 being secured thereto. A spring-pressed pawl 305 is pivotally mounted on the bracket 110, and engages the ratchet wheel 304 so as to permit movement thereof in only one direction. A winding key 306 is secured to the ratchet wheel 304 and is loosely

mounted on the end of the shaft 300 so as to wind up the clock spring 303.

The shaft 107 protrudes through the bracket 110 and has slidably but not rotatably mounted thereon a grooved clutch element 307. A pair of bevel gears 308 are loosely mounted on the shaft 107 in position to mesh with the bevel gear 301. The portion of the shaft between the gears 308 is splined and there is slidably mounted thereon the clutch mechanism 307 so as to rotate therewith. The ends of the clutch member 307 are toothed to form ratchet members 309 and 310. The contiguous faces of the bevel gears 308 are provided with complementary ratchet members 311 and 312 in spaced relation with the toothed elements 309 and 310, respectively. The grooved clutch element 307 is engaged by a pin 314 secured near one end of a T shaped lever 315 pivoted at 316 to the bracket 110. The arrangement is such that rotation of the lever 315 about its pivot 316 oscillates the clutch element 307 to engage with one or the other of the bevel gears 308. The bracket 110 includes a lateral extension 318, the outer end of which is provided with a bearing 319 for supporting the shaft 120, which protrudes into the compartment 121 of the torpedo. The portion of the shaft 120 between the bearing 319 and the main part of the bracket 110 is splined as indicated at 320, and there is slidably mounted thereon a clutch element 321 for engaging a clutch element 322, which is secured to the end of the shaft 107. By sliding the clutch element 321 longitudinally with respect to the shaft 120, the shaft 120 may be connected or disconnected from the shaft 107.

For controlling longitudinal movement of the clutch element 321 there is provided an arm 323 pivotally secured as at 324 to the bracket 110, and having a pin 325 engaging a groove in the clutch element 321. The free end of the arm 323 is bent as at 326 and terminates as at 327 in such manner as to engage the dog 302. The arm 323 is normally held in such position that the clutch elements 322 and 321 are in operative engagement by means of a spring 328, one end of which is secured to the arm and the other end of which is secured to the fixed bracket 110. Below the pin 325 the arm 323 is provided with a cam face formed to include a pair of spaced projections 329, 330 with a depression 331 therebetween. A roller 332 is mounted on one end of the T lever 315, which engages the cam surface of the arm 323 and which in the normal position of the T lever registers with the depression 331.

The third arm of the lever 315 is provided with a pin and slot connection indicated as at 333 to a piston rod 353 as will subsequently be set forth. Secured to the end of the rod 353 is a pin and slot connection 333 provided in the lower arm of the lever 315.

For controlling the rotation of the shaft 107 there is provided intermediate the thrust bearings 111 and 112 of the shaft 107 a worm 335 for driving a worm wheel 336 in mesh therewith. Referring more particularly to Figs. 5 and 6, the worm wheel 336 is loosely mounted on a shaft 337 which is mounted for rotation in bearings in the bracket 110. A pair of collars 338 are secured to the shaft 337, and serve to prevent longitudinal movement thereof with respect to the bracket 110. Rigidly pinned to the shaft 337 is a member 340 provided with a projecting dog 342. The proximate face of the worm wheel 336 is provided with a tongue element 343 for engaging the dog 342. One end of the shaft 337 is also splined and

is provided with a cone clutch element 344 slidably mounted on the shaft 337 and rotatable therewith. The cone clutch element 344 engages a stationary clutch element 345 forming in combination therewith a water-tight bearing. The stationary clutch element 345 is recessed as at 346 and is secured in fixed position on the hull 10. The outboard end of the movable clutch element 344 is provided with a pointer or indicator 347 and terminates in a squared end as at 348 for engagement by a socket wrench or other adjusting tool. A compression spring 349 is positioned on the shaft 337 between one of the collars 338 and the clutch member 344 and serves to maintain the movable clutch member 344 in intimate contact with the stationary clutch member 345. The arrangement is such that the pointer 347 indicates on the outside of the torpedo the position of the dog 342.

20 Mounted on the frame 110 is a cylinder 351 in which reciprocates a piston 352 which is attached to a piston rod 353. The end of this rod is provided with a pin 354 which slides in the groove 333. Communicating with opposite ends of the cylinder 351 are two pipes 355 and 356, the other ends of which communicate with ports 357 and 358 in a rotary valve casing 359. Rotatably mounted in this case is a rotary valve 361 (see Fig. 8). The rotary valve casing 359 is secured to the inner face of the torpedo hull 10. The casing is provided with a recess as at 362 accessible from the exterior of the torpedo. The rotary valve 361 is snugly fitted within the base of the casing 359, a packing 363 being provided to form a water tight seal. The exterior end of the valve stem 361 is provided with a square socket 364 for the reception of an adjusting tool. The rotary valve 361 is held tightly in its seat by a projectile 365 which is a part of cap 366, screw threaded upon the inner end of the casing 369. Thus the rotary valve 361 may be rotated by the means of an adjusting tool previous to the discharge of the torpedo and is held in a fixed position thereafter. The rotary valve is provided with two ports 367 and 368. The port 367 registers with the port 357 and the port 368 registers with the port 358. An exhaust port 369 is provided in the casing 359. Opposite to the exhaust port 369 is a port 371 which communicates with one end of a pipe 372, the other end of which communicates with a port 373 in a valve casing 374. Slidably mounted in the casing 374 is a valve stem 375 which is provided with two heads 376 and 377 at either end. Between the head 377 and the casing 374 is a coiled spring 378. The stem 375 is provided with an annular groove 379 which at all times communicates with a port 381. This port communicates with the supply pipe 382. The valve stem 375 is normally held in the position shown in Fig. 2 by means of a spring pressed armature core 383, which is slidably mounted in a solenoid 384.

The antenna 218 passes through the cut off device 390 which is provided with a cutting tool 391 slidably mounted in brackets 392. Pinned to the tool 391 is a collar 393 between which and one of the brackets 392 is a coil spring 394. A cutting block 395 is secured to the hull of the torpedo 10 on the opposite side of the antenna from the tool 391. Secured to the casing 390 is a solenoid 396 which is provided with a spring controlled armature 397, the end of which normally engages the collar 393.

Located adjacent to the flexible conductor 218A

is a contact 401 to which is connected a conductor 402 which extends to one side of the winding of a coil 403 (Fig. 16). The other side of the winding of this coil is connected through the secondary of a transformer 404 to a ground connection 405. One side of the winding 403 is also connected to an oppositely wound coil 406 which is connected to a balancing network which has been shown as comprising an inductance 407, resistance 408 tuned circuits 409 and 413, resistance 10 411 and an inductance 412.

One side of the primary of the transformer 404 is connected to the grid of an oscillator tube 415, the other side of this winding being connected through a coil 416 to one side of the filament 15 417 of the tube 415. The current for this filament is supplied by a battery 418, one side of which is connected to one side of a plate battery 419, the other side of which is connected through an inductance 421 to the plate of the tube 415. Inductance 421 is tuned by a condenser 422. This circuit serves for producing oscillations which are fed into the transformer 404.

Located adjacent to the coil 403 is a coil 423, one side of which is conducted to the grid of a 25 vacuum tube 425. The other side of the coil 423 is connected to one side of the filament of the tube 425 and also to one side of a battery 427, the other side of which is connected to the winding of a sensitive relay 428. The other side of the 30 winding of the relay is connected to the plate of the tube 425. A condenser 429 is connected across the relay 428.

This system is so designed and constructed that when the antenna 218 is trailing behind the 35 torpedo in the water the currents flowing through the coils 403 and 406 will be balanced against each other thus producing no current in the coil 423. If, however, the antenna 218 should come in proximity with a mass of magnetic material such 40 as a ship this balance will be disturbed thereby allowing more current to pass through the coil 403 than the coil 406. This will cause current of the frequency produced by the oscillator 415 to flow in the coil 423 which will be received by 45 the vacuum tube 425 which in turn will cause current to flow through the relay 428.

The armature of the relay 428 controls the flow of current from a battery 432 through a secondary relay 433. The armature of this relay is connected to one side of a battery 434, the other side of which is connected by a conductor 435 to one side of the winding of the solenoid 384. The other side of the winding of this solenoid is connected by a conductor 436 to the front contact of the 55 relay 433. The conductors 435 and 436 are respectively connected by conductors 437 and 438 to the winding of the solenoid 386.

In the modified form of the invention shown in Fig. 17, the conductor 492 is connected to one 60 side of a Wheatstone bridge, three sides of which are made up of the inductances 451, 452, and 453 and the capacities 454, 455, and 456. Across the bridge is connected the secondary of a transformer 457, the primary of which is supplied with high 65 frequency current from a vacuum tube oscillator 458, which is similar in construction to the oscillator 415. Connected to one side of the bridge is a condenser 459, the other side of which is grounded at 461. Across the other terminals of the bridge 70 is an inductance 462, adjacent to which is located the coil 423 which controls the operation of the secondary relay 433 in a manner similar to that shown in Fig. 16.

Before the torpedo is discharged the spring 303 75

is wound by means of a key 306, precaution being taken that the clutch element 307 is centrally positioned as illustrated in the drawings, and the arm 323 is rotated to its fullest extent in a counter-clockwise direction so as to engage the dog 302 and prevent the gear 301 from turning.

Before the torpedo is discharged, the officers in the plotting room determine the angle at which the torpedo will be required to turn after the 10 antenna has been engaged by an enemy battleship as shown by the angle θ in Fig. 19. Accordingly, a socket wrench is fitted to the squared end 348 of the movable clutch element 344 which is thereupon turned through the complement of the 15 angle θ . In turning the clutch element 344, it is necessary to press the socket wrench inwardly against the tension of the spring 349, thereby releasing the movable clutch member 344 from the stationary member 345. The pointer 347 accurately 20 indicates the extent of movement. When the pointer 347 indicates the angle 18° minus θ , the wrench is removed, thereby restoring the clutch element 344 under control of the spring 349 into intimate contact with the stationary clutch element 345 and locking it in the adjusted position and simultaneously making the joint watertight so that no water can enter the torpedo after it has been fired. It will be seen that this adjustment also positions the dog 342 in the same angular 25 position as the pointer 347 and that, therefore, the angle comprehended by the dog and the tongue 343 will be the required angle θ . The order transmitted from the plotting room to the 30 torpedo room includes in addition to information as to the extent of the angle θ instructions as to whether the turning movement should be made in a clockwise or a counter-clockwise direction. If the line of enemy battleships is moving to the right, the adjustment should be made 35 in a clockwise direction while if the enemy is moving to the left the adjustment should be made in a counter-clockwise direction.

Before the torpedo is fired a socket wrench is inserted into the opening 364 and the rotary 40 valve is turned either to the position shown in Figure 2 or to a position in right angles thereto (as shown in Fig. 18) depending upon whether the enemy is moving to the right or left as seen from the firing ship.

Pointer 535 is also set to regulate the speed of the clockwork mechanism for causing the retard valve 530 to be operated over the desired period of time. Cam 538 is set to control the extent of movement of the valve and thereby govern the 45 amount by which the speed of the torpedo is retarded.

Just before being discharged, the usual firing pin (not shown) is released so as to permit explosion of the charge when the torpedo strikes the target. The various electrical circuits shown 50 diagrammatically in the drawings are also closed by means of a conventional switch connected in series therewith but omitted from the drawings for the sake of simplicity, and the source of supply of fluid medium 16 is turned on. The torpedo is thereupon discharged from its tube and the driving means 15 actuated to rotate the shafts 12, 14 and the propellers 11, 11.

When the torpedo starts upon its course, it is 55 automatically maintained thereon by means of the gyroscopic action of the massive element 95 which is held fixed in space independently of movements of the torpedo. Thus any change in position of the torpedo with respect to its vertical axis causes a relative movement of the

housing 65 and the mechanism associated therewith as hereinabove set forth. This movement is communicated through to the arm 51 which moves the valve rod 50 either to the right or to the left. Assuming that the valve rod 50 is moved to the right of Fig. 2, the source of fluid medium 16 connected to the pipe 41, delivers fluid medium to the right-hand portion of the cylinder chamber. At the same time, a left-hand port 37 is open. The piston 35 is accordingly moved towards the left. This motion is communicated by the rod 33 to the vertical rudders 30 and the torpedo is steered towards port until the initial position of the housing 65 with respect to the gyroscope stabilizing element 95 is reached. The valve rod 50 is then returned to normal and the piston 35 restored to its initial central position, with the torpedo moving in its original direction of movement.

If it is desired to change the course of the 20 torpedo, from a distant point, an impulse of radiant energy is sent from a distant station. The radiant energy excites the antenna 218, which trails behind the torpedo. The signals are thus transmitted to a receiving circuit as illustrated 25 in Fig. 13, in which they are detected and amplified. The amplified signal energy actuates the relay 219, which in turn closes the circuit including the battery 220, armature and front contact of the relay 219 and winding of the secondary 30 relay 221, thus causing the actuation of the relay 221. A circuit is then closed from one pole of the battery 222 armature and front contact of the secondary relay 221, and the windings of the solenoids 181 and 210 in multiple to the 35 opposite pole of the battery 222, thus energizing the solenoids 181 and 210. The impulse employed for steering the torpedo is relatively short, and does not permit the full actuation of the dash pot piston associated with the solenoid 210. 40 The brush 212 is, therefore, maintained in electrical contact with the segment 208. The impulse is sufficiently long, however, to permit the full movement towards the right of the armature core 180 of the solenoid 181, and the piston 45 197 and the dash pot 196, and thus the pawl 171 engages the next tooth of the ratchet 176. Upon the cessation of the impulse the relays 219 and 221 and the solenoids 181, 210 are de-energized 50 and the armature core 180 is accordingly returned to normal under control of the spring 183, the armature core 211 being returned under control of its spring. The return movement of the core 180 causes the ratchet 176 to be moved in a counter-clockwise direction one step, and 55 this rotates the shaft 174 and the commutator 170 one step. Return movement of the dash pot piston 197 is retarded by the closing of the trap valve 199 and thus the brush 205 remains in contact with the insulating segment 209 for a 60 pre-determined length of time which is determined by the adjustment of the needle valve 200. After this interval the brush passes on to the conducting segment 208. A circuit is closed from one pole of the battery 171, conductor 281, 65 brush 212, conducting segment 208, brush 205, conductor 233, contact springs 185, 186, conductor 217, brush 192, conducting segment 187 of the commutator 170, the upper segment 190 now being connected to the brush 191 as a result of the movement of the shaft 174 one step, conductor 233, winding of the solenoid 156, common return conductor 232 to the opposite pole of the battery 171. This circuit remains closed 70 only until the dash pot piston 197 returns to 75

normal, when the brush 205 moves off of the conducting segment 208 and on to the insulating segment 207. The energization of the solenoid 156 actuates the valve stem 154 to connect the fluid source 16, by way of the branch pipe 160 to the upper portion of the cylinder 151, it being noted that the lower portion of the cylinder is at this time open to the atmosphere by way of a port 153. The piston 150 is forced downwardly, thus moving the rack 140 and rotating the gear 125. The adjustment of the needle valve 200 is such that the solenoid 157 remains energized sufficiently long to cause the operation of the rack 140 to its full extent, thus rotating the gear 125 through one-half a revolution. It will be noted that the duration of the electrical impulse transmitted to the solenoid 156 is independent of the duration of the transmitted signal impulse, and thus complete operation of the rack 140 is assured independently of the operation of the sending station. In the present example, the gear 125 is moved initially in a clockwise direction as seen in Fig. 3, and this motion is communicated by means of the pawl 126 engaging the ratchet 122 to the shafts 120 and 107 thus turning the shaft 107 in a clockwise direction through an angular distance of 180°. Upon the de-energization of the solenoid 156, the rack 140 returns to normal under control of the spring 143, but the pawl 126 is at this time held out of engagement of the ratchet 124 (see Figs. 2 and 3) because the lug 131 in this direction of movement strikes the trip 133 to prevent operation of the ratchet 124.

As a result of the single operation of the solenoid 156, the shaft 107 is turned through an angular distance of 180° in one direction. This movement is communicated through the bevel gears 106, 105 and thus to the shaft 102 for actuating the worm 101 and thus moving the cover 64 through a predetermined number of degrees in a clockwise direction, as seen in Figs. 9 and 11. The cover 64 in its movement carries the member 76 with it so that it is shifted relatively to the plate 96 in a clockwise direction. The operation is then the same as previously described for the automatic control, namely, the valve rod 50 is shifted to admit fluid under pressure to the right hand end of the cylinder 36, thus causing the piston 35 to move and shift the rudder 30 in a clockwise direction so that the torpedo is directed toward the left until it has moved through the same number of degrees that the cover 64 has been moved. When it has reached this position, the member 76 has come into a neutral position with respect to the plate 96 and the torpedo will then proceed upon the new course as required.

If it had been desired to direct the torpedo to the right instead of to the left, the general sequence in operation is the same excepting that two short impulses would have been transmitted from the sending station instead of the one impulse as already described. In this instance, the controller 170 is stepped around two steps, thus connecting in the circuit the conducting segment 188 instead of the conducting segment 180. In this case the solenoid 157 is operated instead of the solenoid 156 and the rack 140 is moved upwardly as seen in Figs. 2 and 3. This rotates the gear wheel 125 through one-half a revolution in an opposite direction, that is, in a counter-clockwise direction as seen in Fig. 3 and this motion is communicated by means of the pawl 126 engaging the ratchet 124 to the shaft 120, thus

turning the shaft in a counter-clockwise direction through an angular distance of 180°. It will be seen that although two impulses are transmitted to the solenoid 157 and that the armature core 180 is reciprocated twice thereby, the dash pot piston 197 is merely moved to the right at the commencement of the first impulse and is delayed in its retraction after the cessation of the first impulse by the closure of the trap valve 199 and the restricted passage for air through the needle valve port 200. After the termination of the first impulse the dash pot piston 197 and the brush 205 start to move gradually to the left under the action of the spring 202 and retarded by the restriction of the valve 200. As long as the brush 205 remains on the insulation 209 the circuits from the batteries 171 will remain open. Before the brush 205 has reached the segment 208 the second impulse is sent which as already described returns the brush 205 and piston 197 to the extreme right-hand position. At the termination of this impulse the brush 205 starts to move gradually to the left again until it engages segment 208, at which time the local circuit is closed from the battery 171, conductor 231, brush 212, conducting segment 208, brush 205, contact springs 185, 186, conductor 217, brush 192, conducting segments 187, 188 of the controller 170, brush 189, conductor 234, winding of the solenoid 157, common return conductor 232, to the opposite pole of the battery 171. It will thus be seen that only a single impulse is transmitted to the solenoid 157. Upon the de-energization of the solenoid 157, the rack 140 returns to normal from the control of the springs 142, but the pawl 126 is at this time held out of engagement of the ratchet 122, because the lug 130 in this direction of movement strikes the trip 132 to prevent the operation of the ratchet 122.

As a result of the single operation of the solenoid 157, the shaft 107 is turned through an angular distance of 180°, and this movement being communicated through the gear train moves the cover 64 in a counter-clockwise direction, as seen in Figs. 9 and 11, thus actuating the rudder 30 in a counter-clockwise direction so that the torpedo is directed towards the right. It will be apparent that by suitably selecting the gears through which this motion is transmitted the course of the torpedo can be shifted to port or to starboard any predetermined number of degrees as a result of the transmission of a radiant energy signal. It has been found desirable, however, to provide gear mechanisms such that the course of the torpedo is shifted through an angular distance of five degrees in response to each impulse.

The course of the torpedo may subsequently be changed as many times as may be desired by the transmission of one short impulse or two short impulses in order to position the controller 170 into the required position. For instance, after the course of the torpedo has been shifted to the right, as above described, if it should be desired to shift it further to the right through an additional angular distance of five degrees, it is only necessary to transmit two additional short impulses. If however, the next deviation of the course is desired to be made to the left a single additional impulse is transmitted.

After the salvo of torpedoes has advanced the required distance in a parallel formation as shown in Fig. 20, it may be desirable to retard the speed of the various torpedoes in order to bring them into the biased position shown in Fig. 21. For

this purpose commutator 170 is stepped around 60 degrees from the position shown in Fig. 13 by a suitable long impulse thereby electrically connecting brushes 525 and 522 and energizing the relays 219, 221 thus closing the circuits of the solenoids 181, 180. The armature core 180 is moved to the right as seen in Fig. 13, thus disengaging the spring 185 from the spring 186. The dash pot rod 195 is moved towards the right at a high speed and the companion dash pot rod is moved to the right at a relatively slower speed, being retarded in its movement by the flow of air through the regulated needle valve. The impulse is sufficiently long to permit both the dash pot rods to be moved to the full extent of their travel and thus the brush 205 engages the insulating segment 209, while the brush 212 is moved sufficiently to engage the conducting segment 213.

A circuit is thus closed from one pole of battery 171 through conductor 231, brush 212, segment 206, conductor 240, brush 525, segment 520, brush 522, conductor 521, solenoid 528, and conductor 529, back to battery 171. This energizes solenoid 528, releases latch 536 and allows cam 533 to begin to rotate. As soon as cam 533 releases rod 531, the valve becomes partly closed due to the action of spring 534. The extent of closing is determined by the position of cam 538. The pressure of the actuating fluid is thereby decreased and the driving turbine correspondingly retarded. The torpedo will then travel at a slower speed until cam 533 has made a complete revolution again cooperating with rod 531, thereby opening valve 530. The speed of rotation of cam 533 determines the period over which the speed of the torpedo will be retarded and the position of cam 538 governs the amount of retardation. The torpedoes will thereafter proceed at their initial speed toward the enemy.

The above mechanism should be so adjusted in the various torpedoes of the salvo that, in response to the long impulse above described, they will be progressively retarded and caused to resume the position shown in Fig. 21, after which they will again advance toward the enemy at their original speed.

The course of the torpedoes can thereafter be controlled by radiant energy in the manner previously described until they have been directed into the proximity of the fleet of battle ships being attacked.

A second long impulse may then be sent bringing the commutator into the position shown in Fig. 13.

A circuit is now closed from one pole of the battery 171, conductor 231, brush 212, conducting segment 213, conductor 240, brush 525, segment 520, brush 524, conductor 526, winding of the solenoid 241, conductor 242, to the opposite pole of the battery 171, thus energizing the solenoid 241. The armature core of the solenoid is actuated, thus unlatching the flexible conductor 218A which then springs away from the contact 218B and engages the contact 401. This causes the antenna 218 to be disconnected from the radio receiving set and connected to the magnetic balance through the conductor 402.

The torpedo now continues on the course which it was on at the time the long impulse was sent and is no longer under radio control but is maintained upon this course by means of the gyroscope as in a manner already described. The magnetic balance, as shown in Fig. 16, as already stated is so designed that there is normally no current flowing through the coil 423 and there-

fore the sensitive relay 428 is normally de-energized as shown. If, however, the torpedo should pass some distance in front of the enemy's ship and the latter should touch or come very close to the antenna, as shown in Fig. 19, the magnetic balance will be disturbed as already described, thus causing the sensitive relay 428 to be energized which in turn energizes the secondary relay 433. This closes the circuit from the battery 434 through the conductor 435, solenoid 384, conductor 436, armature of the relay 433, back to the battery 434, and also closes the circuit from the battery 434 through conductor 437, solenoid 396, conductor 438, armature of the relay 433, back to the battery 434. As soon as the solenoid 396 is energized its core 397 will be drawn to the right, thus releasing the cutting tool 391 which under the action of the spring 394 is driven through the antenna 218, thus severing the same and allowing the posterior portion to be swept away, thus not interfering with the subsequent movements of the torpedo.

The energization of the solenoid 384 causes its armature core to be drawn to the right thus releasing the valve 375 which under the action of a spring 378 is moved downwardly allowing compressed air to pass from the supply pipe 382 to the pipe 372, thence through the port 367 to the pipe 355 and into the right hand end of the cylinder 351. This causes the piston 352 to be moved to the left which rotates the T arm 315 in a clockwise direction about the pivot 316.

The roller 332 of the arm 315 engages the cam face of the projection 329 and oscillates the arm 323 in a clockwise direction about its pivot 324, thus carrying the pin 325 and the slideable clutch element 321 towards the right. The clutch element 321 is thus moved out of engagement with the clutch element 322 and the operative connection between the shaft 120 and the shaft 107 is thereby broken. This action disconnects the radio control mechanism from the steering mechanism. At the same time the end 327 of the arm 323 is removed from engagement with the dog 302 and the shaft 300 is released for rotation under control of the clock spring 303. The bevel gear 301 which is secured to the shaft 300 is thus rotated. At the same time the pin 314 which is secured to one arm of the T shaped lever 315 moves clutch element 307 towards the right and thus causes the ratchet 309 to engage the ratchet 311, thereby coupling the right hand gear 308 to the shaft 107. The shaft 107 is accordingly driven under control of the clock spring 303, the operative connection including the bevel gears, the ratchets, and the clutch element which is splined on the shaft 107. The shaft 107 is thus rotated, and its movement is communicated through the gear train to move the cover 64.

The operation is then the same as previously described for the automatic control and for the radio control, namely, the valve rod 50 is shifted to admit fluid under pressure to the right-hand end of the cylinder 36 thus causing the piston 35 to move and shift the rudder 30 in a clockwise direction so that the torpedo is directed towards the left. It will thus be seen that the torpedo moves in a circular course towards port (see Fig. 19). This operation continues until the tongue 343 of the wheel 336 engages the dog 342, which, as already described, has been turned through the angle $180 - \theta$. When this occurs the rotation of the gear 336 is stopped which also prevents a further rotation of the shaft 107. The top plate 64 of the gyroscopic mechanism is therefore

stopped in this position after being turned through the angle θ . The torpedo will, therefore, turn through the angle θ and then proceed upon a straight course until it strikes the enemy's ship, 5 as indicated in Fig. 19.

If the enemy is moving to the right as observed from the ship from which the torpedo is discharged, the valve stem 361 is turned in a clockwise direction to the position shown in Fig. 10 18. Assuming now that the enemy ship comes in contact with the antenna 218, the solenoid 384 is energized in the manner hereinbefore described and admits fluid under pressure to the pipe 372. As the valve stem 361 has been turned 15 in a clockwise direction, the fluid under pressure, will now pass through the port 367, pipe 356 to the left hand side of the cylinder 351, the piston 352 of which is moved to the right as shown in Fig. 2 and the T arm 315 is moved in a counter-clockwise direction about its pivot 316. The roller 331 engages the cam face of the projection 330 and moves the lever 323 as before to disengage the radio control apparatus and to release the dog 302. The bevel gear 301 is thus 20 rotated under control of the clock spring 303. At the same time the pin 314 of the T arm 315 is moved towards the left, thus moving the clutch member to the left and causing the ratchet members 310 and 312 to be engaged, thus coupling 25 the bevel gear 301 to the shaft 107. As the shaft 300 is moved in the same direction as before, under control of the clock spring 303, but the bevel gear 301 is now coupled to a shaft 107 by means of the left-hand gear 308, the shaft 107 is moved in the opposite direction from that previously described and thus the gyro mechanism for controlling the rudder is moved to turn the course of the torpedo to starboard instead of to port. This action continues until the tongue 343 30 strikes the dog 340, which occurs after the torpedo has turned through the angle θ , after which the course of the torpedo is righted and it assumes a straight course. In this case, however, the torpedo has been turned in the opposite direction to that in which it was turned for the enemy moving to the left. The torpedo will, therefore, turn to the right through the angle θ and then proceed upon a straight course until it strikes the enemy ship in a manner similar to 35 that described in connection with Fig. 19.

In Fig. 20 is shown a fleet of enemy ships 470 and a flock of torpedoes 471 which have been fired in salvo from an attacking destroyer squadron not shown. Should the enemy continue on 5 their original course they would either be struck directly by these torpedoes or else engage the antenna of a torpedo which had already passed in front of the ship thus causing it to circle around as just described so as to strike the ship 0 on the opposite side from the attacking destroyer squadron. If, however, the enemy should discern the torpedoes coming they could head toward them in a well-known maneuver in which event some of the ships in the rear of the line 5 would pass behind the torpedo screen and thus not be endangered by the attack.

This action may be prevented, however, by successively retarding the speed of the various torpedoes to cause them to take a position en 0 echelon, as shown in Fig. 21. In this case were the enemy to head towards the torpedoes as is the usual practice, it is obvious that the torpedoes on the right would still endanger the enemy ships unless they made almost a right angle turn towards the attacking fleet which would entirely

break up the formation of a line and subject the enemy to a very serious disadvantage in gun fire attacks from the attacking battleships.

By retarding the speed as above described it is to be noted that the torpedoes may be run rapidly out toward the battle line while being steered by remote control and, while in proximity to the battle line, may be changed into the formation shown in Fig. 21, after which they again rapidly approach the enemy. The magnetic balance 10 may then be connected whereby, in the case of a miss, the antenna can be acted upon by the hull 15 of the ship, as shown in Fig. 19, bringing the redirecting mechanism into operation.

While certain novel features of the invention 15 have been shown and described and are pointed out in the annexed claims, it will be understood that various omissions, substitutions and changes in the forms and details of the device illustrated and in its operation may be made by those skilled 20 in the art without departing from the spirit of the invention.

What is claimed is:

1. In a self propelled body, a speed changing mechanism, means for setting said mechanism for effecting a predetermined change in speed over a predetermined period of time, means associated with said mechanism for restoring the initial speed at the expiration of said period of time, and means operable by remote control for initiating the operation of said mechanism.

2. In a torpedo, a speed changing mechanism, means for setting said mechanism for effecting a predetermined reduction in speed over a predetermined period of time, means associated with said mechanism for restoring the initial speed at the expiration of said period of time, and means operable in response to radiant energy waves for initiating the operation of said mechanism.

3. In a self propelled body, means for normally 40 maintaining said body on a predetermined course and at a predetermined speed, means responsive to radiant energy for varying said course, means for temporarily changing said speed over a predetermined period of time, and means responsive 45 to radiant energy for operating said speed changing means.

4. In a wireless controlled torpedo, a source of motive power, means for controlling said power whereby said torpedo may be operated at a predetermined speed over a predetermined course, means responsive to radiant energy waves for varying said course, and means responsive to radiant energy waves for temporarily changing the speed of said torpedo by a predetermined 55 amount, means operable under the influence of a metallic hull for redirecting said torpedo, and means responsive to radiant energy waves for rendering said last means operative.

5. In a torpedo having a trailing antenna 60 adapted to receive radiant energy waves, a translating device normally connected to said antenna and adapted to operate a steering mechanism, a speed changing device, means whereby said steering mechanism and said speed changing device 65 may be selectively operated by said translating device, a redirecting mechanism responsive to the influence of the metallic hull for redirecting said torpedo, and means for electrically disconnecting said antenna from said translating device and 70 connecting said antenna to said redirecting mechanism.

6. In a torpedo having driving means and steering means, means responsive to successive short impulses of radiant energy for successively oper- 75

- ating said steering means in opposite directions, a speed changing mechanism and a redirecting mechanism, and means responsive to a long impulse of radiant energy for selectively rendering 5 operative said speed changing mechanism and said redirecting mechanism.
7. A method of forming a salvo of torpedoes into a battle line, which comprises operating said torpedoes at a given initial speed until they reach 10 the proximity of a target, changing the speed of certain of said torpedoes until they assume the desired formation, and thereafter causing said torpedoes to travel at their initial speed.
8. In a torpedo having driving means and 15 steering means, means responsive to short impulses of radiant energy for controlling said steering means whereby the course of said torpedo is varied in one direction, means responsive to two rapid short impulses of radiant energy for 20 steering said torpedo in the opposite direction, a speed changing mechanism, and means responsive to a long impulse of radiant energy for operating said speed changing mechanism.
9. In a torpedo having driving means and 25 steering means, means responsive to a short impulse of radiant energy for controlling said steering means whereby the course of said torpedo is varied in one direction, means responsive to two rapid short impulses of radiant energy for 30 steering said torpedo in the opposite direction, a speed changing mechanism, means responsive to a long impulse of radiant energy for operating said speed changing mechanism being adapted to vary the 35 speed of said torpedo by a predetermined amount for a given period of time and to then restore said speed to its initial value.
10. In a torpedo having driving means and steering means, a selector, means responsive to 40 short impulses of radiant energy for controlling the position of said selector, and means for alternately operating said steering means in opposite directions in successive positions of said selector, a speed changing mechanism and a redirecting 45 mechanism, means responsive to a long impulse of radiant energy dependent upon the position of said selector for operating said speed changing mechanism or said redirecting mechanism.
11. In a torpedo having driving means and 50 steering means, an automatic steering device for normally maintaining said torpedo upon a pre-determined course, a selector, means responsive to short impulses of radiant energy for determining the position of said selector, means responsive to short impulses of radiant energy for varying 55 the position of said automatic steering means whereby said torpedo is steered to the right or left according to the position of said selector, a speed changing mechanism, means for setting said mechanism for changing the speed of said torpedo by a predetermined amount and for controlling the period of such change, means operable by said mechanism for restoring the initial 60 speed at the expiration of said period, means operable in response to long impulses of radiant energy when said selector is in certain positions for causing said speed changing mechanism to operate, a redirecting mechanism comprising means responsive to the proximity of a metallic mass for 65 redirecting said torpedo, and means responsive to a long impulse of radiant energy when said selector is in alternate positions for rendering said redirecting mechanism operative.
12. In a torpedo, a source of compressed air, a 70 compressed air motor for propelling said torpedo,
- a valve for controlling the flow of air to said motor, a cam normally holding said valve in a given position, mechanism for rotating said cam whereby the position of said valve is altered, a second cam, and means for setting said second cam to 5 control the extent of movement of said valve.
13. In a torpedo having a fluid controlled motor, a valve for controlling the flow of said fluid, a cam for holding said valve in a given position, means for causing a single rotation of said cam 10 whereby the position of said valve is temporarily altered, means for controlling the extent of movement of said valve, and means responsive to remote control for initiating the operation of said rotatable cam. 15
14. In a torpedo, a controller, means responsive to a short impulse of radiant energy for moving said controller in one position and for changing the course of said torpedo in a given direction, means responsive to a pair of rapid short 20 impulses of radiant energy for moving said controller two positions and for varying the course of said torpedo in the opposite direction, redirecting mechanism and a speed changing mechanism responsive to a long impulse of radiant en- 25 ergy, and means dependent upon the position of said controller for selectively operating said speed changing mechanism and said redirecting mechanism in response to a given long impulse.
15. In a torpedo, an electrical controller mov- 30 able in steps in response to successive short impulses of radiant energy, a pair of translating devices responsive to short impulses of radiant energy and selectively operable in alternate positions of said controller, and a second pair of trans- 35 lating devices responsive to long impulses of radiant energy selectively operable in alternate positions of said controller.
16. In a torpedo, a trailing antenna, means 40 associated with said antenna for receiving radiant energy waves, a relay operated by said receiving means, an electrical controller, step by step mechanism for operating said controller in response to short impulses and operable to selectively vary the course of said torpedo in opposite directions at 45 alternate positions of said controller, and speed changing mechanism, responsive to long impulses and operable in alternate positions of said controller, a redirecting mechanism, and means operable in alternate positions of said controller for 50 permanently disconnecting said trailing antenna from said receiving means and connecting said antenna to said redirecting mechanism.
17. In a torpedo, a trailing antenna, means as- 55 sociated with said antenna for receiving radiant energy waves, a relay operated by said receiving means, an electrical controller, step by step mechanism for operating said controller in response to short impulses and operable to selectively vary the course of said torpedo in opposite directions at 60 alternate positions of said controller, speed changing mechanism responsive to long impulses and operable in certain positions of said controller, redirecting mechanism comprising an electromagnetic balance operable in other positions of said controller in response to a long impulse, and means whereby the influence of a metallic hull destroys said balance and causes said mechanism to operate to alter the course of said torpedo in 65 a predetermined manner. 70
18. In a vehicle, a vehicle body, a driving de- 75 vice on said body for driving said vehicle at an initial speed, means for changing said initial speed to a modified speed, an interval-measuring device on said body, means controlled by said interval-

- measuring device for changing said modified speed to a different speed, and means for causing said interval-measuring device to operate for but a single interval, whereby to manoeuvre said vehicle.
5. 19. In a torpedo, a torpedo body, a driving device on said body for driving said torpedo at an initial speed, means for changing said initial speed to a modified speed, a definite time measuring device on said body and means controlled by said 10 time measuring device for changing said modified speed back to said initial speed, and means for causing said time-measuring device to operate but for a single time interval, whereby to manoeuvre said torpedo.
15. 20. In a torpedo, a torpedo body, a driving device for propelling said torpedo at an initial speed, means for changing said speed to a reduced speed, an interval-measuring device on said body, means controlled by said interval-measuring device for changing said speed back to the initial speed, means for causing said interval-measuring device to measure but a single interval, and means for adjusting the length of said interval for the desired manoeuvre.
5. 21. The method of manoeuvring a salvo of torpedoes into a battle line which comprises discharging the salvo of torpedoes and causing them rapidly to approach the battle line on a given course in parallel formation, changing to an 0 echelon formation in the same course, and thereafter causing said torpedoes to travel in echelon formation.
5. 22. The method of manoeuvring a salvo of torpedoes into a battle line which comprises discharging the salvo of torpedoes and causing them rapidly to approach the battle line on a given course in parallel formation, changing the speed of the torpedoes to effect an echelon formation in the same course and causing said torpedoes 5 under control of mechanism located exclusively on the torpedoes themselves to resume the initial rapid speed while in said echelon formation.
5. 23. The method of manoeuvring a salvo of torpedoes into a battle line which comprises discharging the salvo of torpedoes in a given formation and causing them rapidly to approach the battle line while in said formation, changing the speed of some torpedoes to change the 10 formation and then controlling said torpedoes by mechanism located exclusively within said torpedoes themselves to cause said torpedoes to travel at the initial rapid speed in the new formation.
24. The method of manoeuvring a salvo of torpedoes which comprises firing the torpedoes in straight line formation along a straight course, and causing the torpedoes to approach the battle line in echelon formation along said straight 15 course.
25. The method of manoeuvring a salvo of torpedoes into a battle line which comprises discharging the salvo of torpedoes substantially together in a given formation along a straight 15 course and then causing the torpedoes to take a predetermined different formation along said straight course.
26. In a vehicle, a vehicle body, a driving device for propelling said vehicle at an initial speed, 20 means for changing said speed to a reduced speed, means located exclusively on the vehicle body for changing from said reduced speed back to the initial speed, and means for adjusting the length during which said vehicle travels at reduced 25 speed according to the desired manoeuvre.
27. In a torpedo, a torpedo body, a driving device on said body, governing devices on said body for causing said driving device to propel said torpedo at an initial speed, means to adjust said 30 governing device to cause said driving device to propel said torpedo at a predetermined reduced speed and thereafter back at said initial speed, and means for adjusting the interval during which said torpedo travels at said reduced speed. 35
28. In a vehicle, a vehicle body, a driving device, governing devices for causing said driving device to propel said vehicle at an initial speed, means to adjust said governing device to cause said driving device to propel said vehicle at a 40 reduced speed and thereafter back at said initial speed, and means on said body for adjusting the time at which said vehicle travels at reduced speed, the distance through which said body travels at reduced speed and the value of said 45 reduced speed.

JOHN HAYS HAMMOND, JR.
